UNITED STATES PATENT OFFICE.

HENRY ADALBERT SMITH, OF ELGIN, ILLINOIS.

DESIGN FOR A SAFETY-RIPPER CASE.

46,889.

Specification for Design.

Patented Jan. 26, 1915.

Application filed February 13, 1914. Serial No. 818,613. Term of patent 7 years.

To all whom it may concern:

Be it known that I, HENRY ADALBERT SMITH, a citizen of the United States, residing at Elgin, in the county of Kane and State of Illinois, have invented a new, original, and ornamental Design for a Safety-Ripper Case, of which the following is a specification, reference being had to the accompanying drawing, forming a part thereof.

The figure is a plan view of a case for a safety ripper, showing my design.

I claim—

The ornamental design for a safety ripper case as shown.

In witness whereof, I have hereunto subscribed my name in the presence of two witnesses.

HENRY ADALBERT SMITH.
